DESIGN FOR A DECORATIVE PAPER OR THE LIKE

Frank McIntosh, New York, N. Y., assignor to Lenthalic Incorporated, New York, N. Y., a corporation of New York

Application July 5, 1935, Serial No. 57,527

Term of patent 7 years

To all whom it may concern:

Be it known that I, Frank McIntosh, a citizen of the United States, residing at New York city, in the county of New York and State of New York,
have invented a new, original, and ornamental Design for a Decorative Paper or the like, of which the following is a specification, reference being had to the accompanying drawing, forming part thereof:

The figure represents a plan view of a continuous sheet of decorative paper bearing my design.

Such a sheet may be employed, for example, to cover the curved surface of a cylindrical container.

I claim:

The ornamental design for a decorative paper
or the like substantially as shown and described.

In witness whereof I affix my signature.

FRANK McINTOSH.
